Primary Examiner—Holly Baynham
Attorney, Agent, or Firm—Lathrop & Clark LLP[57] **CLAIM**

The ornamental design for a leg for a window repair fixture, as shown and described.

DESCRIPTION

FIG. 1 is a perspective view of a fixture leg showing the new design;

FIG. 2 is a top plan view thereof;

FIG. 3 is a bottom plan view thereof;

FIG. 4 is a first side elevational view thereof;

FIG. 5 is a second side elevational view thereof;

FIG. 6 is a back elevational view thereof; and,

FIG. 7 is a front elevational view thereof.

The broken line showing of a window repair fixture is for illustrative purposes only and forms no part of the claimed design.
